(57) **CLAIM**

The ornamental design for a putting mat, as shown and described.

DESCRIPTION

FIG. 1 is a first perspective view of a putting mat showing the claimed design;

FIG. 2 is a second perspective view thereof;

FIG. 3 is a third perspective view thereof;

FIG. 4 is a fourth perspective view thereof;

FIG. 5 is a right-side view thereof, the left-side view being a mirror image thereof;

FIG. 6 is a bottom view thereof;

FIG. 7 is a top view thereof;

FIG. 8 is a front view thereof; and,

FIG. 9 is a back view thereof.

Broken lines in the figures show portions of the putting mat that form no part of the claimed design.

1 Claim, 9 Drawing Sheets
